UNITED STATES PATENT OFFICE.

CHARLES RUFFLY, OF RIXHEIM, GERMANY.

DESIGN FOR WALL-PAPER.

SPECIFICATION forming part of Design No. 29,956, dated January 3, 1899.

Application filed December 6, 1898. Serial No. 698,479. Term of patent 7 years.

To all whom it may concern:

Be it known that I, CHARLES RUFFLY, a subject of the Emperor of Germany, residing at Rixheim, Alsace, Germany, have invented and produced a new and original Design for 5 Wall-Paper, of which the following is a specification, reference being had to the accompanying drawing, forming a part thereof, which is a plan view of a section of wall-paper embodying the features of my design.

The design consists in a bouquet A of flowers and foliage, in the composition of which 10 a group of flowers of the hibiscus, gloxinia, and achimenes type, together with foliage

sprays, constitutes the body portion of the 15 bouquet, while from said body portions of running vines are represented as trailing downward bearing flowers of the morning-glory type.

The flowers and foliage at B and C represent repeats of portions of the bouquet A.

I claim—

The design for wall-paper herein shown and described.

CHARLES RUFFLY.
